SAMUEL NORMAN SMITH, OF LYNCHBURG, VIRGINIA.

AUTOMATIC RAILWAY GATE.

Application filed March 5, 1925. Serial No. 13,316.

This invention relates to an automatically operated railway gate, particularly adapted to be installed at grade crossings where the traffic is not heavy enough to warrant the employment of a gate tender.

The general object of the invention is to provide a gate which will remain normally closed, but which may be opened by an automobile or other vehicle when it approaches the crossing, unless a train is in the block, in which case a device is actuated for positively locking the gate until the train has left the block.

For attaining the foregoing results, various novel instrumentalities have been devised, the structure and operation of which will be fully described in connection with the accompanying drawings, which illustrate the same in their preferred form.

20 In the drawings:

Figure 1 is a plan view illustrating the installation of the invention at a grade crossing.

25 Figure 2 is a plan view of one of the gates and mechanism for actuating it, the same being shown on an enlarged scale.

Figure 3 is a vertical section taken on the line 3—3 of Figure 2.

30 Figure 4 is a vertical section taken at right angles to the plane of Figure 3.

Figure 5 is a vertical section through the mechanism for delaying the actuation of the gate.

35 In carrying out the invention, a gate is installed at each side of the railroad track, and, as shown in Figure 1, extends across the right hand half of the roadway immediately in front of the track. Each gate com-

40 prises two bars 10, which, when the gate is closed, meet or overlap at the center, as shown in Figures 2 and 3. Each of the bars 10 is secured at its outer end to a shaft 11, which is journaled in alined bearings 12 at the top of a pair of posts 13 which are securely mounted at the side of the roadway, or at the center line thereof, as the case may be. A drum 14 is secured to the

45 shaft 11 between the alined bearings 12, and is suitably protected from the weather by a hood 15 secured to the tops of the posts 13. A cable 16 is secured at its upper end to the drum, and at its lower end is secured to one end of a bar 17 which extends trans-

50 versely of the roadway, the other end of the bar being supported by a similar cable 16.

The bar 17 is secured underneath the upper end of an inclined platform 18, the lower end of which is mounted for rocking movement in a cavity 19 extending transversely of the road.

60 Beneath the platform 18 there is formed a pit 20, within which is secured a base block 21 for supporting a cylinder 22, or a plurality of such cylinders. The cylinder 22 has ears 23 secured to its lower end, and pivotally supported on a pivot pin 24 mounted in the block 21. A piston 25 is mounted for reciprocation within the cylinder 22, and has a piston rod 26 pivotally connected at its upper end, as shown at 27, to a block 28 secured to the under side of the platform 18. A packing gland 29 surrounds the piston rod 26 to prevent leakage.

65 Suitable weights 30 are secured to each gate bar 10 which over-balance the weight 70 of the platform 18, and normally hold the gate closed, as shown in full lines in Figure 3. When, however, an automobile or other vehicle is driven onto the platform 18, its weight applied to the drums 14, through the 80 medium of the cables 16, overcomes the effect of the weights 30, and swings the gate bars upwardly, as indicated by dotted lines in Figures 3 and 4. A stop bar or curb 31 is 85 preferably formed on the upper face of the platform 18 to indicate where the vehicle should stop. The cylinder 22 is adapted to contain oil or other liquid, as indicated at 32, to retard the movement of the piston 25, and prevent the platform 18 from dropping too suddenly, and to compel the vehicle to come to a stop before the gate is 90 opened.

95 A small pipe 33 leads from the lower end of the cylinder 22 to an auxiliary cylinder 34, which is connected by a small pipe 35 to the upper end of the cylinder 22, so that when the weight of the platform and vehicle acts upon the piston 25, the liquid 32 is gradually forced out of the lower portion of the 100 cylinder to permit the piston to descend. The liquid is supplied to the cylinder 22 by means of a filler pipe 36, which is provided at its outer end with a cup 37. A check valve 36^a is interposed in the pipe 36 105 in order to prevent the liquid from being forced back when the piston 25 is forced downwardly.

110 In order to further retard the movement of the gate, the flow of liquid through the

pipe 33 is opposed by a plunger 38 slidably mounted on a hollow stem 39 within the auxiliary cylinder 34. The plunger 38 is urged toward the lower end of the cylinder 34 by an expansive coiled spring 40, the upper end of which is seated in a cap 41 adapted to be adjusted vertically by a screw 42, thereby adjusting the tension of the spring. The lower end of the stem 39 has a port 43 normally covered by the plunger 38, but adapted to be uncovered when the plunger is forced upwardly by the pressure of the liquid when it is forced through the pipe 33. The stem 39 also has a number of smaller ports 44 toward its upper end through which the liquid may escape into the upper end of the cylinder 34, and thence through the pipe 35 into the upper end of the cylinder 22. Thus, it will be seen that upon the application of downward pressure to the piston 25, due to the weight of the vehicle on the platform 18, the liquid 32 is gradually transferred into the upper end of the cylinder 22, permitting the piston 25 to descend and open the gate. As soon as the vehicle has passed, the weights 30 will cause the gate to close, forcing the liquid back into the lower part of the cylinder 22.

The normal operation of the gate, as heretofore described, is predicated upon the condition that no train is near the crossing. A valve 45, located in the pipe line 35, is normally open, but when a train approaches the crossing, this valve is automatically closed, thereby preventing the transference of the liquid 32, and as a consequence positively preventing the descent of the piston 25 and the opening of the gate. The position of the valve 45 is controlled by means of a lever 46 intermediately secured to the valve, and normally held in a position to open the valve by a weight 46^a suspended from one end of the lever.

In order to close the valve 45 when a train approaches, a section of track, extending for a suitable distance to either side of the crossing, is bonded together and separated from the remainder of the track by insulation or a gap 47 to form a block. A solenoid 48, mounted within the pit 20, is connected to the respective rails of the block by a circuit which includes wires 49 and 50, and a battery or other source of electric energy 51. The core of the solenoid 48 is pivotally connected to one end of a lever 52, which is intermediately fulcrumed on a pedestal 53 within the pit 20, and is connected at its other end by a link 54 to the lever 46 at the end opposite to the weight 46^a. As the train enters the block, the wheels and axles thereof complete the circuit through the wires 49 and 50, and the solenoid 48 actuates the lever 52 and consequently the lever 46, to close the valve 45 to prevent the transference of the liquid 32, and thereby

prevent the actuation of the gate until the train has left the block.

In addition to the mechanism provided for automatically actuating the gate by the weight of the vehicle, it is preferred to provide means for manually actuating the same if desired. This means includes a rock shaft 55 journaled horizontally beneath the platform 18, and provided with a crank 56 which normally lies against the surface of the roadway. An arm 57 extends laterally from the shaft 55, and is connected by a link 58 to a block 59, which is secured to the under side of the platform 18 adjacent the block 28. The crank 56 then may be lifted manually to depress the platform 18, and to actuate the gate in the same manner as if a vehicle were driven onto the platform. A suitable door 60 is preferably provided to afford access to the pit 20 for replenishing the liquid in the cup 37, or for making any repairs which may be necessary.

From the foregoing description, it will be understood that the gate at either side of the crossing is normally closed. As the motorist approaches the crossing from either direction, therefore, he is confronted by a closed gate, and will naturally slow down as he approaches the platform 18. The vehicle is then driven slowly onto the platform 18 until the front wheels reach the ridge 31. If the screw 42 has been properly adjusted, it will be necessary for the vehicle to pause in this position for a few moments while the piston 25 gradually moves to the bottom of the cylinder 22 and raises the gate bars 10, and if a train has entered the block defined by the insulation or gap 47, the valve 45 is closed and the gate will not open to permit the vehicle to pass until the train has left the block. It will be seen, therefore, that the gate is positively and effectively controlled without the presence of a gate tender.

While I have shown and described in considerable detail the specific construction and operation of the invention in its preferred form, it is, of course, obvious that various modifications may be devised in the form and relative arrangement of the various instrumentalities which cooperate to effect the desired result. It is, therefore, my purpose to include within the scope of the appended claims all such modifications which mark no material departure from the salient features of the invention.

What is claimed is:

1. In a device of the character described, the combination of a crossing gate normally closed, a platform in front of the gate, mechanism operable under normal conditions by the weight of a vehicle on the platform to open the gate, liquid controlled means for retarding the action of the opening mechanism, and means cooperating therewith for

automatically locking the platform and gate against movement when a train is near the crossing.

2. In a device of the character described, 5 the combination of a crossing gate normally closed, a platform operable under normal conditions by a predetermined weight on the platform to open the gate, means for retarding the action of the opening mechanism without adding materially to the weight required to open the gate, and means actuated by a train, when it approaches the crossing, to cooperate with the retarding means and lock the platform and gate 15 against movement.

3. In a device of the character described, the combination of a crossing gate normally closed, a platform in front of the gate and depressible by the weight of a vehicle, 20 mechanism operable to open the gate upon depression of the platform, a cylinder normally containing liquid and having a restricted outlet, a piston reciprocable in the cylinder and connected to the platform for 25 retarding the depression thereof, and means for stopping the passage of the liquid through the outlet to positively prevent the depression of the platform and the opening 30 of the gate when a train is near the crossing.

4. In a device of the character described, the combination of a crossing gate including a bar normally extending transversely above the roadway, a horizontal rotatably 35 mounted shaft to which the bar is secured, a drum secured to the shaft, a platform suspended at one end from the drum and depressible by the weight of a vehicle to rotate the drum and swing the gate bar upwardly, liquid control means for retarding the movement of the platform and the consequent movement of the gate bar, and means cooperating with the retarding means 40 to lock the platform and gate against movement when a train is near the crossing.

5. In a device of the character described, the combination of a crossing gate including a bar normally extending transversely above the roadway, a horizontal rotatably 50 mounted shaft to which the bar is secured, a drum secured to the shaft, a platform suspended at one end from the drum and depressible by the weight of a vehicle to rotate the drum and swing the gate bar upwardly, a cylinder adapted to contain liquid and having a restricted port, a piston reciprocable in said cylinder and connected to the platform to retard the movement of the latter, and means operable when a train 55 is near the crossing to positively prevent the expulsion of the liquid from the cylinder, thereby locking the piston, platform and the gate against movement.

6. In a device of the character described, 60 the combination of a crossing gate, includ-

ing a bar normally extending transversely above the roadway, a horizontal rotatably mounted shaft to which the bar is secured, a drum secured to the shaft, a platform suspended at one end from the drum and depressible by the weight of a vehicle to rotate the drum and swing the gate bar upwardly, liquid controlled means for normally retarding the depression of the platform, and means for controlling the liquid to positively prevent said depression when a train is near the crossing.

7. In a device of the character described, the combination of a crossing gate normally closed, a platform in front of the gate, 80 means operable upon depression of the platform to open the gate, a vertically disposed cylinder beneath the platform adapted to contain liquid, a piston reciprocable in said cylinder and in supporting relation to the platform, a restricted passageway connecting the lower end of the cylinder with its upper end, and means operable when a train is near the crossing to stop the circulation 85 of liquid through said passageway, thereby preventing the movement of the piston, platform and gate.

8. In a device of the character described, the combination of a crossing gate normally closed, a depressible platform in front of the gate, means operable upon the depression of the platform to open the gate, a vertically disposed cylinder beneath the platform adapted to contain liquid, a piston reciprocable in said cylinder and in supporting 95 relation to the platform, means normally permitting the gradual expulsion of the liquid from beneath the piston as the piston and platform are depressed to open the gate, and means automatically operable 100 to prevent said expulsion when a train is near the crossing.

9. In a device of the character described, the combination of a crossing gate normally closed, a depressible platform in front of the gate, means operable upon depression of said platform to open the gate, a vertically disposed cylinder beneath the platform adapted to contain liquid, a piston reciprocable in said cylinder and in supporting relation to the platform, a restricted passageway connecting the lower end of the cylinder with its upper end and permitting the gradual transference of the liquid from the lower end of the cylinder to the upper end 110 as the platform and piston are depressed, and means automatically operable to prevent such transference and thereby prevent the opening of the gate when a train is near the crossing.

10. In a device of the character described, the combination of a crossing gate normally closed, a depressible platform in front of the gate, means operable upon depression of the platform to open the gate, a vertically dis-

posed cylinder beneath the platform adapted to contain liquid, a piston reciproable in said cylinder and in supporting relation to the platform, a restricted passageway connecting the lower end of the cylinder with its upper end, a valve controlling said passageway, a lever secured to the valve, a weight connected to one end of the lever and normally actuating the lever to hold the valve open, and means connected to the other end of the lever and automatically operable to close said valve when a train is near the crossing.

11. In a device of the character described, 15 the combination of a crossing gate normally closed, a depressible platform in front of the gate, means operable upon depression of the platform to open the gate, a vertically

disposed cylinder beneath the platform adapted to contain liquid, a piston reciproable in said cylinder and in supporting relation to the platform, a restricted passageway connecting the lower end of the cylinder with its upper end, a valve controlling said passageway, means normally operable to hold said valve open, a solenoid, means automatically operable, when a train is near the crossing, to energize said solenoid, and means operated by the solenoid, when energized, to actuate said lever to close said valve.

20 In testimony that I claim the foregoing as my own, I have hereunto affixed my signature.
